UNITED STATES PATENT OFFICE.

ORREN S. ELLITHORP, OF CHICAGO, ILLINOIS, ASSIGNOR TO DEERING HARVESTER COMPANY, OF CHICAGO, ILLINOIS.

CORN-SHOCKER.

SPECIFICATION forming part of Letters Patent No. 726,891, dated May 5, 1903.

Application filed August 9, 1902. Serial No. 118,986. (No model.)

To all whom it may concern:

Be it known that I, ORREN S. ELLITHORP, of Chicago, in the county of Cook and State of Illinois, have invented certain new and useful Improvements in Corn-Shockers, of which the following is a full description, reference being had to the accompanying drawings, in which—

Figure 1 is a perspective view of the shock-forming standard of a corn-shocking machine with my improvements thereon; and Figs. 2, 3, and 4 show the details of construction of the same.

This invention may be regarded as an improvement on the construction of the shock-forming standard shown in the patent granted to Frank A. Ryther, No. 681,513, dated August 27, 1901.

The object of the invention is to facilitate the vertical adjustment of the folding radial arms in devices of this kind used on corn-shocking machines.

In the drawings, A is a portion of the rotary table of the corn-shocking machine, and B the main portion of the standard suitably sustained on the table. It is preferably made of square pipe and maintained in its position by a pin projecting up from the center of the table which enters it, as shown by the dotted lines in Fig. 1.

Secured to the lower end of the standard B by set-screws or otherwise is the core-foot hinge-block C, having various lugs c, between which the ends of the core-foot levers D are pivoted. Upon the said core-foot levers D are the lugs d, adapted to receive the core-foot lever-links l. Surrounding the standard and vertically adjustable thereon by means hereinafter described is the core-arm hinge-block E, provided with various lugs e. Between each pair of lugs are pivoted the arms F, which have the inner upturned ends f, as shown in Fig. 2.

G is a ring surrounding the standard above the core-arm hinge-block and having a groove in its lower surface, its outer rim cupping over the short extensions f of the arms F. This ring is free to slide on the said standard B and may be pulled upward at any time by the bars H and H'. These bars H and H' are connected at their upper ends to a suitable

mechanism for moving them, which may be readily understood by reference to the patent above referred to and also the patent granted to Joseph M. Shively, No. 681,517, dated August 27, 1901. When the arms F are set free, they fall or drop on their pivots to positions alongside the standard. This takes place only after the shock has been formed and then lifted by means of a suitable crane and swung around to a position ready to be dropped.

In order that the foot-levers D at the foot of the shock-forming standard may also fold, a sleeve J is provided, which also surrounds the standard B. This sleeve J is pivotally connected to the radial arms F by the core-arm links f². Below the sleeve J is also a similar sleeve K. Extending from the lugs k on this lower sleeve K are the core-foot lever-links l, that are hooked into lugs formed on the levers D near their pivotal ends. Connecting the sleeve J with the sleeve K is the rod j, which is rigidly secured at k' to the sleeve K and releasably secured to the sleeve J by passing through the secondary sleeve j², formed upon one side of the sleeve J, the rod j passing through an eye formed on the bolt j³, which is situated intermediate of and adjacent to the bearing-surface of the secondary sleeve j², as shown in Figs. 1 and 4. The arms F and D being thus connected, when the former are set free and fall the latter will also fall.

M M are two rods that are secured at m m to the core-foot hinge-block C, which is attached to the foot of the standard B. These rods M M extend upwardly and parallel with the said standard B and pass through secondary sleeves i² in the core-arm hinge-block E. In these secondary sleeves i², arranged intermediate of the bearing-surfaces, are the eyebolts i³, adapted to clamp the rods M M similar to the manner in which the eyebolt j³ clamps the rod j. The object of all these adjustments is to enable the operator to place the arms F at any suitable distance from the table, as required in operating in short or long corn. The same adjustments are produced in the device shown in the patent granted to Frank A. Ryther, above referred to, and these improvements are directed to making the adjustments easy ones. By loos-

ening the nuts on the eyebolts i^3 and j^3 the sleeves E and J are free to move upward or downward without affecting any of the parts secured to the lower portion of the standard, 5 and by tightening the said nuts the adjusted parts can be held in the desired position. The rods j and M M are preferably round bars; but they may be bars of any form and may be clamped to the castings J and E, respectively, by any suitable means that will admit of securement in any desired position.

Integral with the casting E and extending upwardly from the same on opposite sides of the standard B and within the ring G are two 15 lugs, only one, however, being in view on the drawings. The upper ends of these lugs are provided with outwardly-projecting lips e' , which limit the upward movement of the said ring G.

20 What I claim as my invention, and desire to secure by Letters Patent, is—

1. In a corn-shocker, a shock-forming standard, a hinge-block fixed to the base thereof and provided with a set of radial arms, a second 25 hinge-block sleeved on said shock-forming standard above said fixed hinge-block and also provided with a set of radial arms, rods extending from said fixed hinge-block to said sleeved hinge-block, thereby affording support and adjustment for the latter, and for actuating both sets of arms simultaneously, substantially as described.

2. In a corn-shocker, a shock-forming stand-

ard, a lower set of radial arms secured at the base thereof, a hinge-block supporting said lower set of radial arms, an upper set of radial arms adjustably located directly above the said lower set, a hinge-block supporting said upper set of radial arms, and rods fixed to and extending from the hinge-block supporting the said lower set of radial arms to and adjustably connecting with the hinge-block supporting the said upper set of radial arms, all combined substantially as described. 45

3. In a corn-harvester, a shock-forming standard, a hinge-block fixed to the base thereof and provided with radial arms, a sleeve slidably mounted on said standard above the said hinge-block and secured to the lower set of arms by suitable links, an upper hinge-block sleeved on said standard and provided also with radial arms, a second sleeve slidably mounted on the standard below the said upper hinge-block and connected with the upper radial arms by suitable links, rods connecting the said upper and lower hinge-blocks adapted to form a support and means of vertically adjusting the former, and a rod connecting the two slidable sleeves, all combined 55 substantially as described. 60
